METHOD OF CONSTRUCTING REINFORCED CONCRETE BRIDGE

Ulrich Finsterwalder, Munich, Germany

Original application April 11, 1949, Serial No. 86,668, now Patent No. 2,712,750, dated July 12, 1955. Divided and this application May 23, 1955, Serial No. 514,142.

4 Claims. (Cl. 72—8)

The present invention relates to a truss bridge of reinforced concrete and to a method of its construction. This application is a division of my application Serial No. 86,668, filed April 11, 1949, now Patent No. 2,712,750.

Prior to this invention it was the practice, as a rule, to construct bridges of re-enforced concrete extending over a plurality of spans as a continuous beam in form of a plate provided with webs. The span of such bridges is limited because of the extreme weight of such webs with large vertical dimensions. While it is true that the weight may be somewhat reduced by a design of the beams as box-shaped elements better adapted to sustain bending torques, and, therefore, permitting of a slight reduction of the thickness of the beams, structures of that kind are uneconomical for spans of 150 feet or more because of their excessive weight.

Moreover, steps have been taken to increase the vertical dimension of the main beams in a brace-like manner within the region of the middle pillars to thereby increase the zone of the negative bending torques and to decrease the zone of the positive bending torques intermediate the pillars. This development, however, did not result in a substantial increase of the spans of concrete bridges.

Some progress with respect to an increase of the span and the reduction of the weight was attained by the proposition to place the re-enforcing bars outside of the cross-section of the concrete beam proper, and to subject them by special means to a high tensional force using a specially tough steel. Constructions of this kind involve the disadvantage that the concentrated tension set up in the steel bars must be guided around corners and taken up by anchoring means. Such tensional forces must be guided through points of the beam subject to but comparatively small bending torques, e.g. through the cross-section of zero torque. Therefore, the re-enforced concrete structure must be dimensioned at such points to take up much higher forces than would result from the load. The result is a high dead load limiting the spans for economical reasons.

Other designers consider it a drawback that, with the above stated method, the advantages resulting from the so-called bonding effect between the biased steel bars and the concrete element is not attainable in each cross-section thus requiring a higher bias to compensate the effects of shrinking and creeping. Such designers use a bias combined with a bonding effect, that is to say, they subject the steel bars to tension in a so-called tensioning bed and then embed the biased bars over their entire lengths within the concrete. Because of the extreme bias

2

required, complicated and expensive implements must be used for producing it. Using such a method on bridges having several spans would require a sub-division of the structure into a plurality of elements and a subsequent assembly of such elements by means of a rather involved constructing process. It is the object of the present invention to provide a plural-span concrete bridge free from the above discussed shortcomings of the prior designs and having substantially increased spans permitting at the same time of a simple, economical and inexpensive way of construction.

According to the present invention this object is attained by the combination of the following features: The mean supporting elements are designed as cantilevers freely extending from each of the pillars in both directions, the opposed ends of adjacent cantilevers being separated by a gap. The cantilevers are constructed as trusses of re-enforced concrete. Such concrete trusses are built up by progressively forming successive truss sections starting from the pillars without the use of any scaffold supported on the ground, the re-enforcing tension-bars being anchored by the use of elements as ordinarily employed in the steel building art.

In a preferred embodiment of the present invention 25 the cantilever trusses are subject to negative bending torques preferably over their entire lengths as distinguished from a limited zone above the pillars. This effect is attained for instance with a bridge extending over three spans by the provision of a separating gap in the middle 30 of the central span, means being provided for transferring transverse forces excluding, however, the transfer of any torques or longitudinal forces. In such a case the spans of a three-span bridge are preferably chosen at a ratio of 1:2:1 thus arriving at cantilever arms of equal lengths 35 extending from each of the two pillars. With a larger number of spans a similar arrangement may be provided. This provision, however, is not apt by itself to solve the problem with respect to an economical method of construction. This object is attained by the design of the cantilever as a truss and by a special method of its 40 construction.

The present invention relates more particularly to two alternative species of the novel method of constructing the trusses progressively. With the first method the truss beams subject to pressure — hereinafter called "thrust-beams" — are formed by the usual process used in the art of concrete structures, whereas the truss beams subject to tension — hereinafter called "tension-beams" — are constructed by the methods used in the steel building art, the re-enforcing bars for the tension-beams and the thrust-beams being first placed in position in a slack condition whereupon the thrust-beams are formed of concrete. Then the re-enforcing bars for the tension-beams are subjected to tension by removal of the scaffolds and are then surrounded by and embedded in concrete.

In the other species of the novel method of building up the cantilever trusses progressively section by section, both, the tension-beams as well as the thrust-beams of the frame-work are formed in accordance with standard principles used in re-enforced concrete construction, a pressure being set up, however, in the concrete element of the tension-beams by means of a tensional bias produced in the re-enforcing element, the specific pressure so set up in the concrete being substantially of the same mag-

nitude as the specific pressure prevailing in the thrust-beams of the frame-work. To this end, the re-enforcing bars consisting of a material having a high tensile strength are prevented from entering into a bonding relationship to the surrounding concrete either by coating the re-enforcing bars by a plastic or by forming the concrete beam with longitudinal bores or cavities accommodating the re-enforcing bars in spaced relationship to the concrete permitting of a free relative longitudinal displacement. After the concrete has set, the re-enforcing bars extending through the beam are subjected to a powerful bias by use of known implements, the reactionary force of the tension set up in the re-enforcing bars serving to compress the surrounding concrete lengthwise. Subsequently, a bond may be produced between the steel bars and the surrounding concrete element of the thrust-beams by filling up the bores or cavities with cement.

Important advantages in various regards are attained by the present invention.

Owing to the provision of a gap in the center, the bending torques approach zero with decreasing distance from the gap permitting of a particularly light design of the adjacent zones of the adjoining trusses as is desirable on account of their large distance from the pillars, whereas a maximum bending torque resulting from the own weight of the bridge and largely fluctuating torques from the traffic load would result within this zone, were the truss a continuous one. The use of a truss of the described design permits of taking up the torque prevailing at any point with the largest vertical dimension of the truss available at such point. This again entails the admissibility of an extremely light design of the beams over a large range of the truss. While it is true that the bending torques prevailing in the truss within the zone above the pillars will exceed those set up in a continuous beam of the customary design, this consequence is more than off-set by the afore-stated advantage regarding the bending torques produced. The savings in weight of the large middle span result in a surprising increase of the span possible with a given vertical dimension of the bridge above the pillars, such increase amounting to about 30%. With a given span the present invention makes it possible to reduce the dimensions of the bridge thus resulting in savings of concrete and steel enhancing the efficiency. The reduction of the materials required is not purchased at the cost of complicated and expensive construction implements and building methods for producing the beams. Regarding the difficulties involved, the new construction methods do not differ from those ordinarily used in the normal re-enforced concrete construction art.

The elimination of a scaffold supported by the ground offers great advantages in the construction of bridges of large span, particularly in such cases in which such scaffolds are hampering navigation on rivers or are endangered by floods and ice. The novel method of constructing the trusses section by section progressively simplifies the process substantially resulting in a cost reduction. This holds true for both species of the novel constructing method in which one and the same scaffold and the same concrete forms supported by the finished truss sections are used requiring a minimum of capital investment for the constructing implements.

The second species of the constructing method as above described entails the advantageous possibility of adjusting the bias set up in re-enforcing bars, as the work proceeds, to meet the requirements arising in the course of the completion of the truss. Such adjustments take care of the fact that the distribution of the forces set up in the beams changes with the progress of the work, since in the finished truss such distribution is quite different from that prevailing in the initial stages when the truss is in a semi-finished condition and has not yet reached its full length.

Another object of the present invention is a displaceable

scaffold comprising steel beams imposed on the finished joints of the upper chord and projecting therefrom a distance corresponding to one section, such scaffold being so dimensioned as required to support the concrete forms and the load to be taken up in the assembly of one truss section.

Further objects and features of the present invention and the manner in which the same may be performed as well as the advantages attained by the invention will appear from a detailed description of two preferred embodiments of the invention described hereinafter with reference to the accompanying drawings.

In the drawings

Fig. 1 is an elevation of the novel bridge comprising three spans;

Fig. 2 is a partial vertical cross-section through a cantilever truss forming part of the bridge said cross-section being taken within the middle span at a distance from a pillar of about one quarter of the span and shown on an enlarged scale;

Fig. 3 is a partial view of Fig. 1 on an enlarged scale showing the central joint of the two cantilever trusses;

Fig. 4 is an elevation of one section of the truss in a semi-finished condition in which the re-enforcing bars of the tension-beams are not yet provided with a mantle of concrete;

Fig. 5 is a longitudinal section of the same truss section as shown in Fig. 4 in a finished condition showing the position of the re-enforcing bars and the interconnection of the same;

Fig. 6 is a partial longitudinal section through a modified cantilever truss illustrating the second species of the building method;

Fig. 7 is a cross-section taken through the truss shown in Fig. 6 on an enlarged scale;

Fig. 8 is a partial elevation of a semi-finished cantilever truss under construction showing the novel displaceable scaffold and concrete form used to successively construct one section after the other;

Fig. 9 is an end view from the right of Fig. 8.

The bridge shown in its entirety in Fig. 1 embodying the present invention extends over three spans A, B and C at a ratio of 1:2:1. It comprises two cantilever trusses carried by and projecting equal distances from the two pillars 2 and 3. The adjacent ends of the cantilever arms 5 and 6 are separated by a gap 1. The cantilever arms 4 and 7 constituting the spans A and C are supported on embankment rests or foundations 8 and 9 by customary supporting means such as roller bearings and counterweights or other means not shown in detail adapted to transfer forces in a vertical direction.

Each of the two cantilever trusses of identical design comprises an upper chord in form of a plate of re-enforced concrete constituting the road bed, a lower chord of re-enforced concrete preferably in form of a plate, vertical beams between the two chords and diagonal beams adapted to take up tensional forces.

With this arrangement the own weight of the structure produces negative bending torques only in each of the trusses over their entire lengths, whereas the traffic load produces negative torques only in the middle span, i.e. in the cantilever arms 5 and 6 and positive torques in the outer spans i.e. in the cantilever arms 4 and 7. Such positive torques, however, are small compared with the negative torque caused by the weight of the structure and may surpass the same only in the immediate proximity to the embankment rests 8 and 9. In Figs. 2, 3, 4 and 5 details of the structure are shown to illustrate the cantilever truss composed of thrust-beams built up in accordance with the standard practice of re-enforced concrete construction and of tension-beams built in accordance with the standard steel construction practice. Fig. 2 illustrating a cross-section through the middle span taken at a distance of about one quarter of the span from the pillar, shows the lower chord 10 constituted by a standard

plate of re-enforced concrete and the upper chord 11 re-enforced by bundles of steel bars 12 in cross-section. These bundles take up a space of about half of the cross-section of the upper chord the latter forming the road bed. Moreover, Fig. 2 shows a vertical thrust beam which, in the present embodiment, is constituted by a plurality of posts or columns 13 of re-enforced concrete. The diagonal tension-beams 14 shown in Figs. 4 and 5 are not visible in Fig. 2 as they are hidden from view by the posts 13.

Fig. 3 shows the joint between the two cantilever trusses with a gap 1 provided therebetween in the middle of the span B and with a vertical link 15 of known design for the transfer of vertical forces only.

Fig. 4 shows a section of the frame-work truss in a semi-finished condition in which the vertical beams 13 and the lower chord section 10, all subject to thrust, have been completely formed of re-enforced concrete, the scaffolding and the concrete forms having been removed, whereas the re-enforcing bars 12 of the upper chord 11 and the re-enforcing bars of the diagonal beams 14, all subject to tension under the weight of the semi-finished truss-sections, have not yet been provided with a mantle of cement. It will be appreciated that owing to the removal of the scaffolding the thrust beams 10 and 13 as well as the tension-bars 12 and 14 are placed under load.

Now the concrete forms are brought into position as will be described later for the purpose of mantling the tension-bars 12 and 14 with concrete. Fig. 5 shows the finished structure in section illustrating the re-enforcing bars embedded in concrete.

In a modified process the number of re-enforcing bars placed in position in a slack condition for the upper chord sections is limited to the figure required to carry the weight of the bridge. After assembly of the bridge in the condition shown in Fig. 4, additional bars or cables sheathed with sheet metal or a plastic coat adapted to carry the final load are inserted in the concrete form for the upper chord and are then embedded in the concrete. After the latter has set, the additional re-enforcing bars or cables are subjected to a bias of such a degree that the resulting pressure set up in the surrounding concrete is sufficient to prevent any tension from being exerted on the concrete of the upper chord section under the influence of the biggest possible load of the finished bridge.

This process has the advantage that the road bed will have an increased density and that cracks are prevented from forming under load. Another advantage is the reduction of the number of sleeve joints and other connecting elements required to connect the tension-bars of adjoining upper chord sections. Each of the biassed tension-bars is anchored at its two ends only, that is to say at two points and not at any beam junction.

The tension-bars may be arranged and distributed in various manners. They may be arranged in a bundle located in a special zone or they may be distributed over the entire width of the upper chord section. The hollow space between each of the biassed tension-bars or cables and the surrounding sheathing may be filled up with cement.

In building up a bridge constituted by cantilever trusses as shown in Figs. 1 to 5 the following method may be employed:

First two sections of the truss above each of the two pillars 2 and 3 are constructed in accordance with the standard practice using the customary scaffolding and concrete forms except for the tension-beams which are left in semi-finished condition as shown in Fig. 4. Then the auxiliary scaffold shown in Figs. 8 and 9 is brought into position for the purpose of constructing the adjoining sections progressively. This scaffold consists of a plurality of beams 17 arranged parallel to each other

at a suitable distance and distributed over the entire width of the bridge resting on the last two beam-junctions 18 and projecting beyond the end section a distance corresponding to the length of one section as shown in Fig. 8. From such beams the concrete forms 19 are suspended by means of suspending elements 20.

With the aid of this scaffold the lower chord section 21 and the vertical posts 22 positioned thereon are formed of re-enforced concrete and the diagonal tension-bars 23 and the upper chord re-enforcing bars 24 are assembled. The section 21 is formed adjoining the previously finished section abutting against the latter at the joint 26. The tension-bars 23 and 24 are connected by means of connecting sleeves 27 and 28 with those of the preceding truss section. Care must be taken to postpone the mantling of the diagonal tension-bars 23 and of the bars 24 of the upper chord with concrete until the entire cantilever arm has been built up in the described manner up to its end.

The other species of the novel method of constructing the cantilever trusses will now be described hereinafter with reference to Figs. 6 and 7.

Fig. 6 illustrates one section of the cantilever truss differing from that illustrated in Figs. 1 to 5 by the provision of thrust-beams as diagonal braces 30 in lieu of the diagonal tension-beams shown in the first described embodiment. The road bed plate 32 constituting the upper chord 31 of the truss as well as the vertical posts 33 are biassed in a special manner. Only part of the re-enforcing bars 34 of the upper chord are anchored at each beam junction while the rest of the re-enforcing bars 35 extends the whole length of the bridge. Whenever a truss section has been finished and its concrete has set, the short tension-bars of the upper chord are put under tension. In order to prevent the tension bars from entering into a bonding relationship with the surrounding concrete and to thus render a subsequent tensioning possible after the concrete has set, the re-enforcing bars to be subjected to a bias are either coated with a plastic or inserted in hollows or cavities or bores provided in the concrete.

Fig. 7 shows clearly that the tension-bars 34 are anchored at the beam-joints whereas the tension-bars 35 are running clear through the entire length of the bridge. With this mode of construction the truss may be progressively built up section by section with the aid of the auxiliary scaffold shown in Figs. 8 and 9 with slight modifications to suit the requirements.

The term "re-enforcing bars" used in the claims following hereinafter is to be construed as including wires, rods, solid bars, cables or the like. While my invention has been described hereinabove with reference to specific embodiments thereof I wish it to be clearly understood that my invention is in no way limited to the specific features of such embodiments but is capable of numerous modifications within the scope of the appended claims.

What I claim is:

1. A method of constructing a reinforced concrete cantilever truss bridge comprising constructing a center pier, simultaneously constructing truss panels from opposite sides of said pier by placing first short upper chord reinforcing rods, said rods being anchored to the center pier and extending one panel length and second upper chord reinforcing rods extending over a plurality of panel lengths, and vertical post reinforcing rods, these being tension members, then pouring concrete and forming the lower compression chord and compression diagonal strut and encasing in concrete the upper chord and vertical strut rods with said first short upper chord rods left unbonded to the concrete, tensioning said first short upper chord rods after the concrete has set to compress the upper chord, and then progressively repeating in the same manner the erection of adjoining panels until mid-span is reached with the weight of each panel being constructed and the construction equipment being supported

by the preceding completed panel and thereby tensioning said upper chord and vertical strut rods.

2. A method as in claim 1, further comprising connecting the first short bars of one panel to similar bars in an adjoining panel.

3. A method as in claim 2, further comprising bonding said first short bars after they are tensioned to the enclosing concrete.

4. A method as in claim 1, further comprising constructing said upper and lower chords as slabs extending 10 the entire width of the bridge.
